[57] **CLAIM**

The ornamental design for a baby bath, as shown and described.

DESCRIPTION

FIG. 1 is a perspective view taken from the top, front and right side of a baby bath showing my new design;

FIG. 2 is a top plan view thereof;

FIG. 3 is a bottom plan view thereof;

FIG. 4 is a right side elevational view thereof, the left side being a mirror image of the right side shown;

FIG. 5 is a front elevational view thereof;

FIG. 6 is a rear elevational view thereof;

FIG. 7 is a cross sectional view taken on line 7—7 of FIG. 2; and

FIG. 8 is a cross sectional view taken on line 8—8 of FIG. 2; and

FIG. 9 is a cross sectional view taken on line 9—9 of FIG. 2.

FIG. 1

FIG. 2

FIG. 3

FIG. 4

FIG. 5

FIG. 6

FIG. 7

FIG. 8

FIG. 9
